UNITED STATES PATENT OFFICE.

RICHARD H. STRINGHAM, OF BOUNTIFUL, UTAH.

ELECTRICAL DRINK-MIXER.

1,242,493.

Specification of Letters Patent.

Patented Oct. 9, 1917.

Application filed January 12, 1917. Serial No. 142,018.

To all whom it may concern:

Be it known that I, RICHARD HAYEN STRINGHAM, a citizen of the United States, residing at Bountiful, in the county of Davis and State of Utah, have invented certain new and useful Improvements in Electrical Drink-Mixers, of which the following is a specification.

My invention relates to new and useful improvements in drink mixers for soda fountain or bar use for mixing malted milks, egg-nogs, frappés and the like, and has for one object, the construction of an electric mixer which has no fine wires to burn out or brushes to replace, employing no commutator, slip rings, sliding contacts, or flexible connections, and therefore being economical in manufacture and durable and efficient in use.

20 A further object of my invention consists in constructing an electric drink mixer in which a motor of the squirrel-cage type is employed and in which the rotor in itself forms the mixing element.

25 Another object of my invention is to provide a motor of the character mentioned which will operate at higher speeds than the motors now commonly employed in electric drink mixers and which as a result will cause a more rapid and perfect mixing of drinks.

30 Electric mixers as now commonly employed although superior to manual mixing devices are objectionable in that the motor is usually more or less noisy. A further object of this invention consists in constructing a motor which will be quiet in operation, this being accomplished largely by employing the rotor of the motor as the mixing element so that it is immersed in the liquid being mixed which will, therefore, act as a cushioning agent and partially by mounting the casing of the device upon cushioning or shock absorbing supports.

35 A still further object which I have in view is the provision of means for preventing loss of liquid being mixed through overflowing from the mixing container or splashing therefrom.

40 And a still further object of my invention is the construction of a mixer which will be more compact and neater and more

pleasing in appearance than those formerly in use.

With these and other objects in view, my invention will be more fully described, illustrated in the accompanying drawings and then specifically pointed out in the claims which are attached to and form a part of this application.

60 In the drawings:

Figure 1 is a central vertical sectional view of my improved mixer;

Fig. 2 is a horizontal sectional view taken on the line 2-2 of Fig. 1 looking in the direction of the arrows;

Fig. 3 is a fragmentary perspective view of the rotor supporting member and mixing glass;

Fig. 4 is a side elevation of a switch employed for controlling the motor;

Fig. 5 is a sectional view taken on the line 5-5 of Fig. 4 looking in the direction of the arrows;

Fig. 6 is a diagrammatic view of the wiring of the device;

Fig. 7 is a perspective view of the mixer clearly illustrating its compact and neat appearance.

Corresponding and like parts are referred to in the following description and indicated in all the views of the drawings by the same reference characters.

80 My improved electric mixer includes a substantially rectangular metallic, neatly finished casing or housing 10 which forms a support for a mixing glass 11 and which incloses the stator 12 of the electric motor 13. This casing has cushioning plugs 14 of rubber or equivalent material inserted in its base which serve to absorb shocks or jars 85 and render the device quiet and which also serve to prevent slipping of the device upon a polished table or shelf.

90 The form of rotor employed is a single phase alternating current motor of the squirrel-cage type and includes the stator 12 which is built up of laminated iron, the stator rings being clamped between nuts 15 threaded upon bolts 16 passed through the top wall of the casing and anchored by nuts 17. This stator core or element carries the 95 usual two pole two phase winding 18. Co-

operating with this stator is a rotor 19 built up of laminated iron in the form of a disk having a central opening in which is shrunk a bushing or bearing 20 and the squirrel-cage conductors 21 are fixed about its rim. The laminations making up this rotor are also provided with a series of openings 22 alining with each other to form openings completely through the rotor and preferably concentrically disposed therein.

The upper wall of the casing is formed directly above the stator of the motor with an opening 23 through which the base of the mixing glass 11 may pass so that the lower portion of the glass will be disposed within the casing and between the poles of the stator, as clearly shown in Fig. 1. A supporting or armature shaft 24 is provided at one end with a head 25 having a squared socket 26 to engage about a squared plug or boss 27 formed upon the inner side of the bottom of the mixing glass and centrally thereof. This shaft is adapted to revolvably support the rotor 19 within the glass and in spaced relation to the bottom thereof but is itself held against turning through its locking connection with the glass. A vane of sheet metal or equivalent material 28 is proportioned to fit in the upper part of the mixing glass and has its side edges angularly disposed to conform to the taper of the glass. This vane centrally of its width is formed with transverse incisions 29 in order that portions at opposite sides of the incisions may be oppositely outbent to provide half sleeves 30 so that the vane may be slipped over the upper end of the shaft 24 and serve as a centering means for the shaft. This vane also prevents any loss of liquid being mixed through spattering or overflow as will be later pointed out. As the rotor forms the mixing element and is immersed in the liquid being mixed, it is preferably covered with a thin coating of suitable material such as celluloid or collodion so that it may be conveniently cleaned by immersion in water and so that all crevices which might collect foreign matter will be closed.

Screws 31 secured in opposite end walls of the casing by nuts 32, support in one instance a tube 33 of porcelain, fiber, or other non-conducting material and in the other instance a core 34 of an inductive resistance coil 35 having the winding 36. A non-inductive resistance winding 37 is carried by the tube 33. The purpose of these windings will be later pointed out in detail.

Mounted within the housing 10 and supported by a base 38 of insulating material is a switch 39. This switch includes a bracket 40 which pivotally supports a knife-blade 41 movable into engagement with the knife blade contacts 42 of the switch which are in electrical connection with a binding

post 43, a binding post 44 carried by the bracket constituting the other terminal of the switch. A spring 45 fixed to the knife blade and to a stud 47 carried by the base normally serves to hold the switch in open position, its movement being limited by a stop shoulder 48 formed on the bracket. This switch is so disposed that in open position the contact engaging end of the knife blade member of the switch projects so that the positioning of the mixing glass, as shown in Fig. 1, will engage it to swing it and close the switch. Obviously when the glass is removed the spring 45 will immediately swing the switch blade to open the switch.

The stator windings at one terminal are in electrical connection 49 with one of the binding posts of the switch and their opposite terminals are in electrical connections 50 and 51 with the non-inductive resistance coil 37 and inductive resistance winding 36, respectively. One line wire 52 is electrically connected to both resistance coils and the other line wire 53 is connected to the other binding post of the switch. This wiring is clearly shown in Fig. 6. It will, therefore, be seen that one set of coils is in series with the non-inductive resistance and the other in series with the inductive resistance or reactance and that both of these coils are in parallel with the line wire with the result that the current in one coil will lag behind that of another coil and will give rise to a rotating magnetic field.

In operation the rotor is mounted upon the shaft 24 and both the rotor and shaft are inserted in the mixing glass 11, the shaft being turned until it locks with the glass. The vane 28 is then applied to the upper end of the shaft and moved into engagement with the glass to center the shaft and the various ingredients to be mixed are put in the glass. The mixing glass is then positioned in the casing, as shown in Fig. 1, thereby closing the switch and energizing the motor to cause rotation of the rotor and consequent mixing of the various ingredients contained in the glass. The rapid turning of the rotor, of course, causes the liquids contained in the glass to turn and, consequently, climb the sides of the glass but the vane extending diametrically across the upper end of the glass, breaks up the rotating current and prevents overflow from the glass or spattering.

After the drink has been properly mixed the glass is removed from the casing which automatically opens the switch. The shaft 24, together with its vane and rotor, are lifted from the glass and the contents of the glass is emptied into one or more service glasses. Both the mixing glass and the parts of the mixer for operating therewith, namely, the rotor, rotor shaft and vane, may

be readily washed and cleansed through immersion in either cold or hot water as preferred when the device is again ready for use.

5 The motor is adapted to operate on a single phase alternating current of 110 to 120 volts and therefore may be driven by the usual lighting current. The operation of the motor is accomplished through splitting 10 the phase and in one side inserting a non-inductive resistance and in the other side inserting an inductive resistance. This causes the current in one side to lead and in the other to lag which gives rise to a revolving 15 or rotating magnetic field which cuts across the rotor squirrel-cage conductors inducing currents in them which tend to drag the rotor around with the field. As it increases in speed the torque on the rotor becomes 20 greater and greater until its rated speed is approached. With a motor having a two pole winding of this character the rotative speed of the rotor would be the same as the frequency of the alterations of the exciting 25 current if there were no losses but some loss occurs, due to the space between the rotor and stator core. However, an extremely high rotor speed is obtained and the loss is immaterial considering the rapidity with 30 which the mixing is accomplished and the short periods during which the device is used. All current conducting parts are, of course, suitably insulated from the casing.

Although I have illustrated my invention 35 in detail and described its specific structure, it will, of course, be understood that I reserve the right to make any changes or alterations within the scope of the claims.

Having thus described the invention, what 40 is claimed as new is:

1. In a drink mixer, a stator, a di-electric receptacle adapted to be positioned within the stator, a rotor insertible in the receptacle, and means for rotatably supporting the 45 rotor within the receptacle and in the plane of the stator.

2. In a drink mixer, a stator, a di-electric receptacle adapted to be positioned within the stator, a rotor insertible in the receptacle, and means for rotatably supporting the rotor within the receptacle and in the plane of the stator, said means including a shaft disposed axially of the receptacle and locked thereto against turning movement, the rotor 55 being revolvably mounted upon the shaft.

3. In a drink mixer, a stator, a di-electric receptacle adapted to be positioned within the stator, a rotor insertible in the receptacle, means for rotatably supporting the rotor 60 within the receptacle and in the plane of the stator, said means including a shaft disposed axially of the receptacle and locked thereto against turning movement, the rotor being revolvably mounted upon the shaft,

and a vane detachably mounted upon the 65 shaft to extend diametrically of and engage in the upper portion of the receptacle to centralize the shaft.

4. In a drink mixer, a stator, a di-electric receptacle insertible within the stator, a 70 rotor insertible in the receptacle, means detachably engaging with the rotor for revolvably supporting it within the receptacle and in the plane of the stator, current supply conductors for the stator, and a 75 switch in one of the conductors arranged to be closed by positioning of the receptacle within the stator.

5. In a drink mixer, a stator, a di-electric receptacle insertible within the stator, a 80 rotor insertible in the receptacle, means detachably engaging with the rotor for revolvably supporting it within the receptacle and in the plane of the stator, current supply conductors for the stator, a switch 85 in one of the conductors arranged to be closed by positioning of the receptacle within the stator, and means for automatically opening the switch upon removal of the receptacle. 90

6. A drink mixer including a casing, a stator mounted in the casing, the top of the casing being formed with an opening concentric with the magnetic field of the stator, a circuit for the stator, a switch in the casing controlling the circuit, and in substantial alinement with one side of the opening in the top wall thereof, means normally holding the switch in open position, a di-electric receptacle insertible through the 95 opening in the casing to seat within the field of the stator and adapted when so inserted to engage the switch and close it, a rotor insertible within the receptacle and forming a mixing element, and means for 100 rotatably supporting the rotor within the receptacle and in the plane of the stator poles. 105

7. In a drink mixer, a di-electric receptacle formed centrally of its bottom with an upwardly directed squared stud, a shaft enlarged at one end to provide a shoulder and having the enlarged end formed with a squared recess to lockingly engage the stud, 110 a rotor revolvably and detachably mounted upon the shaft and supported by the shoulder, the rotor forming a mixing element and being provided with apertures, a vane detachably connected to the shaft and adapted to seat in and extend diametrically of the upper end of the receptacle to coöperate with the stud and center the shaft, and a stator, the receptacle being proportioned to seat within the stator to locate the rotor in 115 the plane thereof. 120

8. In a drink mixer, a di-electric receptacle formed centrally of its bottom with an upwardly directed squared stud, a shaft en- 125

larged at one end to provide a shoulder and having the enlarged end formed with a squared recess to lockingly engage the stud, a rotor revolubly and detachably mounted upon the shaft and supported by the shoulder, the rotor forming a mixing element and being provided with apertures, a vane detachably connected to the shaft and adapted to seat in and extend diametrically of the upper end of the receptacle to coöperate with the stud and center the shaft, a stator, the receptacle being proportioned to seat

within the stator to locate the rotor in the plane thereof, and means including a switch for supplying current to the stator, the switch being automatically closed by positioning of the receptacle.

9. In a drink mixer, a di-electric container, a stator disposed about the container, and a rotor disposed within the container to be driven by the stator.

In testimony whereof I affix my signature.

RICHARD H. STRINGHAM. [L. S.]
